UNITED STATES PATENT OFFICE.

JAMES F. CRAVEN, OF PITTSBURGH, PENNSYLVANIA, ASSIGNOR TO CRAVEN ENGINEERING COMPANY, OF PITTSBURGH, PENNSYLVANIA, A CORPORATION OF PENNSYLVANIA.

RECEPACLE FOR CONTAINING AND DISCHARGING SEMISOLID AND PASTY SUBSTANCES.

1,025,511.

Specification of Letters Patent.

Patented May 7, 1912.

Application filed October 14, 1910. Serial No. 587,081.

To all whom it may concern:

Be it known that I, JAMES F. CRAVEN, a resident of Pittsburgh, in the county of Allegheny and State of Pennsylvania, have 5 invented a new and useful Improvement in Receptacles for Containing and Discharging Semisolid and Pasty Substances, of which the following is a specification.

This invention relates to receptacles for 10 containing, storing, transporting and discharging semi-solid and pasty substances.

The device is intended more particularly for putting up lubricants in the form of grease and discharging the same into the 15 grease cups of machine or the like and for the purpose of enabling grease to be supplied to the bearings without liability of dirt or grit entering the bearing with the grease, and also to prevent smearing up or 20 soiling the hands of the workman or the machinery. The invention, however, is not limited to this particular use, but is adapted for putting up in a substantially sealed condition any semi-solid or pasty substance and 25 delivering the same from the container in any desired quantity or quantities.

The invention comprises the construction and arrangement of parts hereinafter described and claimed.

30 In the accompanying drawing Figure 1 is a vertical section through the device; and Fig. 2 is a vertical section of the upper portion of the device in a plane at right angles to that of Fig. 1.

35 The container or receptacle may be of any desired size or shape, and may be constructed or built up in any desired way or from any desired material. As shown, the receptacle is formed from a substantially 40 cylindrical tube 1 which may be of sheet metal or other thin substance and as shown is formed from paste or paper board. One end of this receptacle is closed by the head 2 which is shown as composed of sheet metal 45 crimped onto the end of the paper tube.

The other end of the receptacle is closed by means of the head 3 provided with the central discharge opening 4 formed in the threaded projection 5 which may be closed 50 by means of an ordinary screw cap 6. The head 3 is also crimped onto the paper tube, but if desired it may be removably secured to the receptacle or tube 1, such as by means of threaded connection with a threaded ring

crimped on the tube, in order that the same 55 may be taken off for the purpose of filling the receptacle. This latter, however, is not necessary, as the receptacle can be filled through the discharge opening 4. The threaded projection 5 also serves to have 60 screwed thereon a delivery spout 7 when discharging the material from the receptacle.

In the receptacle 1 is a movable piston or follower 10 provided with a cup leather 65 11 or other suitable means providing for a close fit in the receptacle and being yielding so as to maintain a tight fit in the tube in case the latter expands under the pressure of forcing out the substance contained therein. The piston or follower is shown as a solid disk of wood or other suitable material, although if desired it may be stamped up of sheet metal. In order to force the material from the container the piston is 70 moved longitudinally in the tube or receptacle 1. The means for effecting this comprises a suitable flexible member 12, such as a cord, band, wire or the like, which has one end secured centrally to the piston 10 80 as at 13, and then passes over a suitable support at the delivery end of the receptacle and thence returns and passes through a hole 14 in the piston, and a similar hole 15 in the head 2 of the receptacle, and is 85 provided on the outside with a suitable handle 16, loop or other means which can be readily grasped for pulling.

The support at the discharge end of the receptacle may be of various forms, that 90 shown comprising a bar 18 soldered or otherwise secured at its ends to the cap or head 3 and over which the flexible member 12 passes. Preferably a small sheave 20 is mounted on said bar to reduce friction. The 95 bar shown is a piece of round wire on which the flexible member 12 could have a direct bearing without the use of the sheave 20.

In use the receptacle is filled with the 100 grease or other substance at the factory, being filled through the discharge end and while the piston is in the opposite end of the receptacle. Preferably the filling will be done through the discharge orifice 4 as this enables the cross bar 18 and the wire or band 12 to be in proper position. When the receptacle is filled it is closed by means of cap 6, and can then be conveyed to the place 105

of use. It presents a substantially smooth exterior, there being no projections on the outside except the loop or handle 16. In use the cap 6 is unscrewed, and if desired the delivery spout 7 is screwed on to the projection 5. The material is discharged by holding the receptacle in one hand and with the other hand pulling on the cord or wire 12, which causes the piston to move in the 10 receptacle toward the outlet orifice, thereby forcing the pasty substance out from said orifice. Any desired quantity of material can be forced out, and the operation is effected in a manner which prevents the 15 grease from smearing up the machinery which is to be lubricated and without soiling the hands of the workman or carrying grit or dirt into the grease cup. When the desired quantity of material has been discharged the cap 6 may again be screwed into place and the receptacle remains in this condition until necessity for further use. When used for containing butter or the like the contents are protected against the absorption 20 of odors from other substances stored nearby.

The receptacle is intended to be used only once, being filled at the factory and thrown away when emptied. Hence it must be of 30 low cost and necessarily is made of cheap and comparatively weak material and with minimum labor operations. A paper or paste board tube is therefore preferred for the body of the receptacle, but if sheet metal 35 is used it will be of the thinnest gage. On account of the cheap, light construction of the tube it is liable to expand slightly, or assume a slight barrel shape under the pressure of forcing the stiff grease out of the 40 same. The cup leather 11 or similar means is however expandible and in effect forms

an expandible piston or follower so as to maintain a tight fit against the inner wall of the tube and prevents the grease from wasting by escaping past the edge of the 45 follower.

What I claim is:

1. A device of the character described comprising a fiber tube, a head closing one end of said tube and provided with a discharge orifice, a bearing member secured to said head and extending across said discharge orifice, a piston or follower in said receptacle arranged when moved to force the substance out of said discharge orifice. 55 and a flexible member connected to said piston and passing over said bearing adjacent to the discharge orifice and thence extending to the outside of the receptacle and arranged to be pulled upon to move the piston 60 toward the discharge orifice.

2. A device of the character described comprising a fiber tube having an interior unobstructed from end to end, heads closing the ends of said receptacle, one of said heads 65 being provided with a discharge orifice, a bearing member secured to said last named head, a piston in said receptacle arranged to be moved from end to end thereof to force the contents of the discharge orifice, and 70 a flexible member secured to said piston and extending over said bearing member and thence extending to the opposite end of the receptacle and through the head thereon and provided, outside said receptacle with means 75 to be grasped and pulled.

In testimony whereof, I have hereunto set my hand.

JAMES F. CRAVEN.
